UNITED STATES PATENT OFFICE

ELMER MARVIN CAPOUCH, OF RIVERSIDE, ILLINOIS

DESIGN FOR A TUB MAT OR SIMILAR ARTICLE

Application filed April 13, 1931. Serial No. 39,463. Term of patent 3½ years.

To all whom it may concern:

Be it known that I, ELMER MARVIN CAPOUCH, a citizen of the United States, and residing in the village of Riverside, in the county of Cook and State of Illinois, have invented a new, original, and ornamental Design for a Tub Mat or Similar Article, of which the following is the specification, reference being had to the accompanying drawings, forming a part thereof.

On the drawings:

Fig. 1 is a top plan view of my tub mat.

Fig. 2 is a view of the bottom surface thereof.

Fig. 3 is a cross sectional view taken on line III—III of Fig. 1.

I claim:

The ornamental design for a tub mat or similar article, as shown.

ELMER MARVIN CAPOUCH.
